ACOUSTICAL MATERIAL

Clarence E. Olschner, Shreveport, La., assignor to
Earl W. Lesher, Lakewood, Ohio

Application January 15, 1930, Serial No. 421,023

2 Claims. (Cl. 20—4)

This invention relates to acoustical panels or areas and has for an object to provide an acoustical construction that will more thoroughly entrap the sound waves and absorb them than hitherto possible. This is accomplished by providing not only continuous cells but a chain of interlacing continuous cells within the interior of the construction. When sound waves strike the surface of the panel, a large percentage of the sound waves will be admitted into the interior and will there be absorbed during their ramification in any direction around in the interlacing connected air spaces or cells.

With the above and other objects in view the invention consists in certain novel details of construction and combinations of parts that produce interlacing connected air spaces which details are hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a fragmentary perspective view of a fabricated acoustical panel or area constructed in accordance with my invention.

Figure 2 is a longitudinal sectional view on the line 2—2 of Figure 1,

Figure 3 is a plan view of a modified form of the invention,

Figure 4 is a cross-sectional view on the line 4—4 of Figure 3,

Figure 5 is a plan view of another modified form of the invention,

Figure 6 is a transverse sectional view on the line 6—6 of Figure 5,

Figure 7 is a plan view of a still further modified form of the invention,

Figure 8 is a plan view of another modified form of the invention,

Figure 9 is a longitudinal sectional view on the line 9—9 of Figure 8,

Figure 10 is a plan view of a modified form of the invention,

Figure 11 is a plan view of a modified form of the invention, and

Figure 12 is a plan view of a modified form of the invention.

Referring now to the drawings in which like characters of reference designate similar parts, 10 designates a base sheet of sound absorbent material such as "Insulite", "Masonite", "Celotex", 55 felt cotton, wool, hair, wood, plaster, paper, com-

position board, textiles, or other sound absorbing materials. Superposed on the base sheet are transverse parallel strips 11 and superposed on these strips are longitudinal parallel strips 12. The strips 11 and 12 are also formed of absorbent material of the character just described and are fixedly secured together in any preferred manner to form a rigid unitary structure integral with each other and with the base sheet. A membrane 13, preferably formed of 10 burlap or canvas, but it may be paper or other material, is fixed to the outermost layer of strips 12 and forms a surface to receive any desired type of decoration, but the use of a membrane is optional as no acoustic virtue is claimed for the 15 membrane.

It will be observed that the innermost layer of strips 11 produces channels 14 transversely across the fabricated panel and opening through the edges of the panel and that the strips 12 of 20 the outermost layer form channels 15 which extend longitudinally of the fabricated panel underneath the membrane 13 and also opening through the edges of the panel. It will be further observed that the transverse channels 14 25 and longitudinal channels 15 are intercommunicating so that when sound waves strike the membrane 13 they will be admitted into the interior of the fabricated structure and as diagrammatically shown by the curvilinear arrow 16, will 30 there be absorbed during their ramifications in any direction around in the connected spaces or net-work of air cells. The panels may be so assembled that the longitudinal and transverse channels of adjacent panels form a continuation 35 of each other so that long channels reaching through the height and width of room walls may be produced if desired.

The acoustical panel or area may be built up in the factory or built in place in a building 40 or room in which it is to be used. The size and number of layers of the continuous cells, which as above stated are arranged not only in layers but in connected layers, are to be determined by the person who calculates the area of absorbing surface required to correct or serve a given condition.

Figures 3 to 12 illustrate modifications of the invention and show a variety of methods exhibiting a few of the unlimited possibilities of obtaining the interlacing connected cell interior. The different shapes of the material used and the arrangement of these shapes may be determined by the manufacturers to produce interlacing cells by the shapes of the layers. 55

- In Figure 3 there is illustrated an acoustical panel comprising a base sheet 17 on which is superposed a plurality of blocks 18 disposed in rows both longitudinally and transversely of the base sheet, a surface membrane 19 covering the outer layer of the blocks and cooperating with the base sheet in forming a net-work of sound absorbing cells 20 communicating with each other throughout the interior of the fabricated panel.
- 10 The blocks and the base sheet as above described are formed of absorbent material such as indicated in the list of materials above named and are rigidly connected together in any preferred manner to form a unitary structure. The membrane 19 is preferably formed of burlap, textile, decorated paper, wall-paper or other material. The use of membrane 19 is optional and is not calculated to affect the acoustical results, but may be used to enhance the decorative appearance.
- 15 20 In Figure 5 there is shown a fabricated acoustical panel similar in construction to that form of the invention illustrated in Figure 1, with the exception that the additional layer of strips shown is to produce additional channels for increasing the absorbing area of the interior construction per square foot of exposed wall or ceiling area. Any number of layers may be applied to suit the conditions under consideration. In the modified form illustrated, 21 indicates the base sheet upon which there is superposed a layer of parallel strips 22 which extend transversely of the sheet. A second layer of parallel strips 23 is superposed upon them and extends longitudinally of the sheet. An outer layer of strips 24 is superposed upon the strips 23 and these outer strips extend transversely of the panel. A membrane 25 is secured to and conceals the outermost layer of strips 24. As indicated at 26 sound waves striking the panel are admitted into the interior thereof and there will be absorbed.
- 25 30 35 40 In Figure 7 there is illustrated a still further modified form of the invention. This modified form contemplates the use of longitudinal strips 27 which are curvilinear in length, in lieu of the straight strips employed in the form illustrated in Figure 1. A layer of curvilinear strips such as indicated at 27 may be alternated with a layer of straight strips 28 laid transversely thereof. The outer or curvilinear strips are in the present embodiment shown as concealed by the membrane 29 and the inner layer of straight strips is shown as secured to the base 30, the whole fabricated structure being an integral unitary structure having intercommunicating continuous sound absorbing air cells in the interior thereof.
- 45 50 55 In Figure 8 there is illustrated a modified form of the invention of the type shown in Figure 3 which employs blocks instead of strips to produce the intercommunicating continuous sound absorbing air cells. In the modified form shown in Figure 8 rows of square blocks 31 are arranged longitudinally of the base sheet 32 and produce longitudinal channels 33 and transverse channels 34 which communicate with each other at the adjacent corners of each four blocks. The adjacent corners of each four blocks are bridged by a block 35. The blocks 35 are arranged in rows longitudinally and transversely of the fabricated structure. A membrane 36 is secured to the outer face of the blocks 35 and cooperates with the blocks in forming continuous transverse and longitudinal channels 37 and 38 which communicate with each other in the plane of the blocks 35 and also communicate with the transverse and longitudinal channels formed between the blocks 31. Inter-

posed between the base 32 and blocks 31 are additional blocks 39 which connect the corners of each four adjacent blocks 31 and are substantially the same in size and register with the blocks 35 as best shown in Figure 9. Thus, there is formed between the base 32 and blocks 39 longitudinal air channels 40 and transverse air channels 41. As indicated at 42 all of the above described channels are intercommunicating.

5 10 15 In Figure 10 there is illustrated the use of circular blocks instead of square blocks. The circular blocks 43 are arranged in rows longitudinally and transversely upon the base sheet 44 and each adjacent four blocks are connected by circular blocks 45, the latter blocks being arranged in rows transversely and longitudinally of the structure. A membrane 46 is secured to the outer face of the blocks 45. In this modified form also the rows of blocks form intercommunicating channels longitudinally and transversely not only between the blocks of superposed rows.

20 25 30 35 40 In Figure 11 there is illustrated the use of square blocks 47 having the corners 48 beveled, the blocks 47 being arranged in rows longitudinally and transversely of the base sheet 49. Superposed upon and connecting the corners of each four adjacent blocks 47 are blocks 50 which are of octagonal shape. A porous membrane 51 is secured to the outer faces of the blocks 50. In this embodiment the longitudinal channels 52 and the transverse channels 53 formed between the blocks 47 are of comparatively small magnitude while the spaces between the blocks 50 are of such magnitude as to constitute enlarged air cells 54 which communicate with each other longitudinally and transversely of the structure as well as with the longitudinal and transverse channels between the blocks 47.

45 50 55 60 65 70 75 In Figure 12 there is illustrated the use of blocks 55 which are approximately square in outline with the exception that the sides are curved inwardly and the corners rounded. These blocks are secured to the base sheet 56. Superposed on the blocks 55 are blocks 57 of octagonal shape, each of the blocks 57 connecting together the rounded corners of four adjacent blocks 55. A porous membrane 58 is secured to the outer face of the blocks 57. In this modified form the channels between the blocks 55 are of such shape that both longitudinally and transversely of the structure enlarged spaces 59 alternate with constricted spaces 60. In other respects the intercommunicating channels between both sets of blocks function substantially the same as those above described and illustrated in Figure 11 to entrap sound waves.

80 85 90 95 Throughout the preferred and modified forms of the invention it is now clear that the fabricated acoustical construction provides an interior in which a continuous chain or net-work of intercommunicating channels or air cells are arranged longitudinally and transversely of the structure and communicate with each other not only in the plane of the structure but at right angles to the plane of the structure. This labyrinth of intercommunicating air cells within the interior of the acoustical construction permits of sound waves which strike the surface of the construction being absorbed during their ramifications in any direction around in the connected air cells.

Having thus described the invention, I claim:

1. A fabricated acoustical panel built up of a base sheet and a plurality of layers of hollow blocks, the layers being laid flat upon each other

and in intimate contact with each other, the individual blocks of each layer being spaced at the edges thereof from each other, the spaces between said individual blocks forming air channels opening through the edges of the panel, the channels of contiguous layers intersecting each other and communicating at their intersections to provide a labyrinth of air cells through which sound waves may ramify longitudinally, transversely and perpendicularly to the plane of the panel.

10 2. An acoustical wall member formed of fibrous

materials for walls of rooms and the like comprising a base member and a plurality of superimposed layers of uniformly spaced members arranged in rows, said rows being uniformly spaced from each other a distance equal to the space between said members, the members in each row of each layer being disposed symmetrical to the space between the members of adjacent rows of the adjoining layer and of greater width than said space.

5
